SEWING MACHINE

Horace F. Gruman, St. Louis, Mo., assignor to
Geoffrey Stevenson, Buffalo, N. Y.

Application April 12, 1937, Serial No. 136,466

48 Claims. (Cl. 112—177)

This invention relates to new and useful improvements in sewing machines generally, although more particularly to a machine of the blind stitch type adapted especially for hemming operations.

Heretofore, unsuccessful attempts have been made on vertical needle machines to produce a flat overedge hem seam. In forming these prior seams, the hem was folded back onto the body fabric and the needle was directed through all three fabric layers, and consequently when the seamed hem was returned to its normal position, a ridge of fabric which formed the hinge, extended along the line of seam.

One of the principal objects of this invention is to provide a blind stitch sewing machine for producing a flat overedge hem seam without folding the hem back onto the body fabric.

Another object of the invention is to provide a continuously rotatable ridge forming element for projecting a ridge or node of fabric into needle penetrating position, whereby either all "anchor" stitches, or a predetermined combination of "anchor" and "skip" stitches may be formed.

Another object of the invention lies in the provision of a chaining-off finger which is upwardly yieldable to accommodate the passage thereunder of either cross seams or thicker fabrics.

With these and other objects in view which will more fully appear, the nature of the invention will be more clearly understood by following the description, the appended claims, and the several views illustrated in the accompanying drawings.

In the drawings:

Figure 1 is a front elevation of a sewing machine constructed in accordance with my invention.

Figure 2 is a left end elevation thereof,

Figure 3 is a rear elevation of the machine,

Figure 4 is a top plan view of the machine,

Figure 5 is a vertical section taken on the line 5—5 of Figure 4,

Figure 6 is a vertical section taken on the line 6—6 of Figure 4,

Figure 7 is a horizontal section taken on the line 7—7 of Figure 1,

Figures 7^a and 7^b are detail views showing the driving connection for the feed lift rock shaft,

Figure 8 is an enlarged plan view of the presser foot, showing the ridge forming element, the trimming mechanism, and the stitch forming elements,

Figure 9 is an enlarged plan view of the foot per se,

Figure 9^a is a detail side elevation showing the fabric guiding slot in the foot,

Figure 10 is a perspective view of the needle driving mechanism,

Figure 11 is a perspective view of the spreader driving mechanism,

Figure 12 is a perspective view of the looper driving mechanism,

Figure 13 is an enlarged front elevation of the movable trimmer,

Figure 14 is an end elevation thereof,

Figure 15 is a rear view of the movable trimmer,

Figure 16 is a bottom plan view thereof,

Figure 17 is an enlarged perspective view of 15 the work clamp,

Figure 18 is an enlarged perspective view of the chaining-off finger,

Figure 19 is an enlarged plan view of a hemmed seam constructed by my invention,

Figure 20 is a cross section taken on the line 20—20 of Figure 19,

Figure 21 is a detail view showing more or less diagrammatically, the seam and the stitch forming elements, the needle being shown at its extreme forward position,

Figure 22 is a similar view but showing the spreader holding the needle thread loop open for entrance by the needle,

Figure 23 is a similar view but showing the 30 looper thread loop in position to be entered by the needle,

Figure 24 is a detail plan view showing a seam produced by a single thread,

Figure 25 is a detail plan view showing a seam 35 produced by three threads,

Figure 26 is a side elevation of a modified disc construction,

Figure 27 is an end elevation thereof,

Figure 28 is a detail plan view of a two thread 40 seam produced by my machine when using the disc shown in Figures 22 and 27,

Figure 29 is an enlarged side elevation of the ridge forming disc,

Figure 30 is a vertical section taken on the line 45 30—30 of Figure 29,

Figure 31 is a horizontal section taken on the line 31—31 of Figure 29, and

Figure 32 is a plan view showing the edge of a superposed fabric stitched to a body fabric. 50

Like reference numerals designate corresponding parts throughout the several figures of the drawings.

My invention is directed to a blind stitch type of sewing machine for forming a flat seam when 55

joining superposed layers of fabrics by a line of elastic 2-thread overedge stitches.

The seam

One of such seams as shown in Figure 19, includes a base layer A and a superposed layer B, the latter being preferably formed by a hem fold of the base layer and having an inner edge b. The line of stitches is formed by a needle thread C and a looper thread D. The needle thread is formed into a series of equally spaced loops 5 which are disposed in parallel planes arranged at right angles to the line of seam. The needle loops first pass under the inner edge b of the hem fold, then certain of said loops enter and emerge from the base layer A as at the points 6 to form "anchor" stitches, and then the bights 7 thereof are projected through the hem fold B, and the connecting portions 8 between the loops being exposed and lying along the side of and in parallelism with the inner edge b of the hem. Other needle loops will not enter the body fabric but will enter and pass upwardly through the hem to form "skip" stitches. However, it is possible by my invention to form all "anchor" stitches, or various combinations of "anchor" and "skip" stitches. The looper thread D is formed into a series of equally spaced loops 9 which are disposed in parallel planes inclined to the needle loops 5. The looper loops 9 project through the bights 7 of the needle loops and over the hem fold B and their bights 10 overlap the inner edge b of the hem fold and are concatenated with the necks of the next adjacent needle loops, the connecting portions 11 of the looper thread extending in a line which parallels the inner edge b of the hem fold.

It will, therefore, be seen that the seam produced on my machine is flat and is therefore devoid of the objectionable ridge of the seam heretofore made on a vertical needle machine.

The main frame

My machine for forming the flat seam above described includes a main frame E which includes a hollow standard 12 having hollow upper and lower arms 13, 14 extending laterally from the left side thereof, the free end of the upper arm being provided with a transverse and upwardly opening recess 15 forming a resultant horizontal arm extension 16 and a vertical end well 17, the outer or left hand end of the arm extension 16 being formed centrally with a vertical recess 18 forming resultant front and rear bearing lugs 19, 20.

The main shaft

A main shaft 21 extends longitudinally along the upper arm 13 and across the standard 12 and is suitably journaled therein, the left hand end of the shaft extending across the recess 15 above the arm extension 16 and being journaled in the end wall 17, the arm extension 16 and the end wall 17 thus cooperating to form an extended bearing for the shaft.

The presser foot

A horizontal presser foot F having an opening 22 is located below the arm extension and is rigidly secured thereto by spaced vertical arms 23, 24.

The needle driving mechanism

A horizontal needle shaft 25 is journaled in the spaced bearing lugs 19, 20 and is therefore located below and at right angles to the main shaft 21, and directly above the opening 22 of

the presser foot F. Attached to the forward end of the needle shaft and projecting towards the left thereof, is a needle arm 26 and attached to said arm is a curved needle 27 which carries the needle thread C. A rock arm 28 which is fixed to the needle shaft intermediate the bearing lugs 19, 20 is driven from the main shaft by an eccentric 29 fixed thereon in the recess 15 and a cooperating pitman 30 which extends upwardly through the recess 18. Thus, the needle will be reciprocated horizontally over the opening 22 once for each rotation of the main shaft, the forward or penetrating stroke of the needle being from left to right.

The looper and the driving mechanism therefor

A looper 31 cooperates with the needle 27 to move a loop of looper thread D into position for entrance by the needle, and a spreader 32, which in the present case is non-threaded, cooperates with both the needle and the looper to present a loop of the needle thread C to the looper. Thus a needle thread loop 5 will be projected through a looper thread loop 9 at the left hand side of the seam and a looper thread loop 9 will be projected through a needle thread loop 5 at the right hand side of the seam. It will also be noted that the stitch forming mechanism, as shown, comprises the needle 27, the loop taker or threaded looper 31, and the loop taker or non-threaded spreader 32, and that they operate entirely above the presser foot.

The looper includes a beak 33 and an attaching shank 34 arranged at substantially right angles to each other, the beak being provided with a thread eye 35 near its point and with a thread guide eye 36 at its heel. Fixedly mounted on the presser foot F in rear of the needle path, is a bearing 37 which inclines upwardly towards the left, and journaled thereon is the hub 38 of a bell crank lever 39 which includes a forwardly extending inclined arm 40 to which the shank 34 of the looper is attached by a screw 41. The beak 33 of the looper projects downwardly to the left, and when the lever 39 is oscillated laterally in a slightly arcuate path across the line of seam and in an inclined plane. The looper in its forward movement travels from right to left and the path of travel inclines downwardly and rearwardly, the looper eye 35 being just below and in line with the needle travel when the looper is at the end of its stroke and when the needle is at the beginning of its forward or penetrating stroke. The other arm 42 of the bell crank lever 39 extends laterally and is pivotally connected to the forward end of an adjustable link 43, the rear end of the link being pivotally connected to a downwardly extending rock arm 44 of a bell crank lever 45 which includes a horizontal shaft 46 and an upwardly extending arm 47, the shaft 46 being located in rear of the main shaft and journaled in the frame arm 13 and in the end wall 17 thereof. A driving eccentric 48 is fixed to the main shaft and is connected to the arm 47 by a pitman 49, the arm 47 being provided with a segmental slot 50 and the pitman being adjustable along the slot and secured in an adjusted position by a clamping pin and nut assembly 51.

Thus, by means of this adjustment the stroke of the looper may be shortened or lengthened as desired. It will be noted that the bell crank lever 39 oscillates about an axis inclined to the vertical, and that the bell crank lever 45 oscillates about a horizontal axis.

The term "backward and forward" as applied to the needle and to the looper, has reference to their strokes, and is not to be considered with respect to the front and the back of the machine.

5 *The spreader and the driving mechanism therefor*

The spreader 32 comprises a forwardly bowed beak which inclines downwardly from its horizontal shank 52 to its free end which terminates in a forwardly projecting V-shaped finger 53. The shank 52 is fixed to the lower arm 54 of a lever 55 which is provided with an extended horizontal hub 56 journaled on a horizontal bearing pin 57 fixed to a forwardly extending wing 58 of a bracket 59 attached to the horizontal arm extension 16 at the right of the needle shaft 25, the wing 58 being laterally inclined towards the shaft to thereby position the longitudinal axis of the bearing pin 57 at an inclination to the main shaft 21. The upper arm 60 of the lever 55 is connected by a pitman 61 to an eccentric 62 fixed on the main shaft intermediate the needle driving eccentric 29 and the looper driving eccentric 48. The spreader finger is thus reciprocated in a path which is inclined to the line of feed and in a plane which is substantially at right angles to the general plane of the looper travel. The spreader finger thus moves forwardly and upwardly over the needle, starting from a point adjacent the presser foot opening 22 but on the right hand side thereof, and then moving forwardly to the left passing under the looper 31 which is then on its forward stroke, and in advance of the point thereof.

35 Thus, as the needle begins its backward stroke, the spreader will pick up the needle thread loop and carry it forwardly into position to be entered by the looper, and the looper will then continue its forward stroke and position its looper thread loop into position to be entered by the needle during the next forward stroke of the latter.

It will be noted that the needle moves forwardly from the left hand side of the presser foot opening 22 and that the looper moves forwardly from the right hand side of said opening, whereas the spreader moves across both the needle path and the looper path.

50 *The chaining-off finger*

In order for the machine to continue the formation of stitches, either at the end of a seamed fabric or between a seamed fabric and a fabric which has just been inserted in the machine, I have provided the presser foot with a chaining-off finger 63, the needle thread loops extending across and below the finger and the concatenated looper thread loops extending across and above the finger. This finger is positioned directly above the presser foot opening 22 and projects rearwardly from a laterally extending supporting shank 64 which is positioned in a transverse groove 65 formed in the upper face of the foot and on the right hand side of the opening, the finger extending across the path of the needle and the needle having its movement below the finger. The shank 64 is attached to the front arm 66 of a lever 67 which is fulcrumed as at 68 on the bracket 59. The rear arm 69 of the lever is urged upwardly by a coil spring 70 which is positioned between said rear arm and the foot. The spring therefore functions to maintain the shank 64 seated in the groove 65 but permits the

finger to be elevated against the tension of the spring when either cross seams or thicker fabrics are fed under the finger. It will be noted that the fulcrum 68 of the supporting lever 67 is located in rear of the free end of the finger 63 5 and consequently when the finger is elevated the attaching end of the finger will be raised a greater distance than said free end, thus facilitating the enchain loops slipping off the finger.

10 *The trimming mechanism*

It is desirable to trim the inner edge of the hem B prior to the hem being stitched to the body fabric A, and to provide means for turning the hem in advance of the trimming operation. 15 To this end, the presser foot F is provided in front of the needle path, with an L-shaped opening comprising a longitudinal opening 71 and a communicating lateral opening. The lateral opening is formed by a forwardly extending foot 20 portion 73 and a rearwardly extending foot portion 74. The under face of the portion 73 inclines downwardly and rearwardly, and the upper face of the portion 74 inclines downwardly and rearwardly, said upper and lower faces conjoint- 25 ly forming a resultant rearwardly and downwardly inclined slot 75 for receiving the nose 76 of a folder 77 which is secured to a bracket arm 78 removably mounted on the front wall of the lower frame arm 14, the folder extending around 30 the rearwardly projecting portion 74. The longitudinal opening 71 is located in front of and in register with the opening 22, and the lateral opening is located on the right hand side of the opening 71. A horizontal ledger blade 79 is seated in a transverse groove 80 formed in the upper face of the foot on the left of the opening 71 and in rear of the nose 76 of the folder, and is adjustably clamped therein by a screw 81, the cutting edge of the blade preferably projecting 40 slightly into the opening 71 and lying in parallelism with said opening. A horizontal movable blade or knife 82 cooperates with the ledger blade 79 to trim the upturned edge of the hem, the movable blade being reciprocable across the rear 45 end of the opening 71, and being provided with a toe or extension 83 which is maintained in yieldable sliding contact with said ledger blade. The cutting edge of the movable blade inclines rearwardly towards the cutting edge of the ledger 50 blade to provide a shearing cutting action between the blades, and the toe 83 is located at the rear end of the cutting edge of the movable blade. The movable blade is removably attached to a holder 84 by a longitudinally extending clamp 85 55 and screw 86, the holder and the clamp being conjointly formed with a dovetailed groove for receiving the blade. The heel of the holder 84 is pivotally connected by a transverse pin 87 to the lower arm 88 of a supporting lever 89 which is 60 fulcrumed on a horizontal stud or bearing 90 fixed to and extending forwardly from the bracket wing 58. The upper arm 91 of the lever is pivotally connected by a link 92 to an eccentric pin 93 fixed to the front end of the needle shaft 65 25. The holder 84 is provided with a rigid and upstanding lever arm 94 which is located intermediate the cutting edge of the movable blade and the pivot 87, and a coil spring 95 is interposed between the arm 94 and the lower arm 88 70 of the supporting lever 89 and functions to maintain the movable blade in yieldable contact with the ledger blade. The left hand end of the clamp 85 terminates in a guide 96 for the trimmed off strip, the guide being curved downwardly and 75

rearwardly and terminates in close fitting relation to the toe 83.

From the foregoing it will be observed that both the needle and the movable trimmer blade are operated from the needle shaft, that the needle moves from left to right during its forward or penetrating stroke, and that the movable blade moves from right to left during its cutting stroke.

10   The edge guide

An edge guide G which is mounted on the front end of the presser foot for lateral adjustments, functions to guide the inner edge of the hem to the trimmer blades.

15   The work clamp

Cooperating with the under face of the presser foot F to clamp the fabric against the thrust of the needle, is a horizontal work clamp 97 which is rigidly secured along its right hand edge to the upper end of a vertical shank or post 98 having a vertical slot 98a formed therein. The work clamp is provided with three parallel and longitudinally extending feed slots of equal length, there being two side slots 99, 100 and an interrupted intermediate slot comprising a front portion 101, a rear portion 101a, and an intermediate "chaining-off" bridge 101b. The intermediate slot 101 is centered with respect to the aligned openings 22 and 71 in the foot, and the side slots 99, 100 are located on opposite sides of said openings. These slots extend from a point in front of the slot 71 to a point well in rear of the opening 22. The work clamp is supported on the lower frame arm 14 for vertical movements with respect to the presser foot, and to this end the shank 98 is supported for slidable movements between vertical guides 102, 103, the guide 102 being a part of the end wall 104 of said lower frame arm 14, and the guide 103 being removably mounted on said wall. The end wall 104 between said guides is provided with a vertical slot and fixed to the shank and projecting through the slot into the interior of the frame arm, is an abutment or arm 106 having a depending pilot stud 107. An adjusting screw 108 is threaded upwardly into the bottom wall 109 of the frame arm 14 directly below the stud 107, and a coil spring 110 is interposed between the stud and the screw for yieldably urging the work clamp upwardly and for normally retaining said clamp in yieldable engagement with the presser foot. In order to depress the work clamp 97 against the tension of the spring 110, I have provided a treadle or knee-press operated chain 111 which extends upwardly through an opening 112 in the bottom wall 109 of the frame arm 14 and is connected indirectly at its upper end to the work clamp, as will be explained hereinafter.

60   The feeding mechanism

Cooperating with the under face of the presser foot F to feed the fabric rearwardly are a 4-motion main feed dog 113 and a 4-motion differential feed dog 114. The main feed dog 113 includes two long side sections 115, 116 and a short intermediate section 117 which operate in the rear portions of the feed slots of the work clamp. The side sections are disposed on opposite sides of the presser foot opening 22 and extend forwardly to a point slightly in front of the needle path, but the intermediate section is disposed wholly in rear of the needle path and in rear of said opening. The differential feed dog includes two long side sections 118, 119 and a short intermediate

section 120 which operate in the front portions of the feed slots in the work clamp. The side sections are disposed on opposite sides of the presser foot opening 71 and extend forwardly to a point slightly in front of said opening, but the intermediate section 120 cooperates with the foot immediately in front of the opening 71 and its rear end terminates in front of the trimmer ledger blade 79. The side sections 115, 118 and 116, 119 of the feed dogs are arranged in overlapping relation for engaging the body fabric through the combined length of both dogs.

The differential feed dog 114 is attached to the upper end of a vertically disposed differential feed bar 121 which is fulcrumed at its lower end as at 122 to the front arm 123 of a horizontal feed lift lever 124 which is fulcrumed as at 125 on the shank 98 of the vertically movable work clamp 97. Pivotedly mounted on the rear arm 126 of the lever as at 127 is a slide block 128 which is slidably mounted in a forked rock arm 129. The arm 129 is fixed to and extends from a fed lift rock shaft 130 which is journaled in the rear portion of the lower frame arm 14. The shaft 130 is provided with a rock arm 131 located within the frame arm 14 and this arm is oscillated from a horizontal counter shaft 132, which extends lengthwise of the arm and across the standard, by a pitman 133 which is pivotally connected at its lower end to the rock arm and has its upper end engageable with a driving eccentric 134 fixed to said counter shaft as shown in Figs. 7a and 7b. The shaft 132 is driven from the main shaft 21 by a 1-to-1 gear coupling located within the standard 5 and comprises a driving gear 135 fixed to the main shaft, a driven gear 136 fixed to the driven counter shaft 132, and an intermediate gear or idler 137 journaled on the standard. Although I have specifically shown and described a gear coupling between the main shaft 21 and the counter shaft 132, any other known mechanical driving means having a 1-to-1 ratio may be employed and I therefore use the term "gear coupling" in its broadest sense. Thus during each rotation of the main shaft the differential feed dog 114 will be raised and lowered. Journaled in the lower frame arm 14 in rear of the rock shaft 130 is a differential feed travel rock shaft 138 which is actuated from the driven shaft 132 by means of a rock arm 139 located within the lower frame arm 14 and fixed to the shaft 138, and a pitman 140 which is pivotally connected as at 141 to said rock arm and has operative connection with the driven shaft through the medium of an adjustable eccentric fixed to said driven shaft and indicated as an entirety by the numeral 142. Fixed to the left hand end of the rock shaft 138 is a rock arm 143 and a horizontal link 144 is pivotally connected at its rear end as at 145 to said rock arm and is pivotally connected at its front end to a stud or pin 146 fixed to the differential feed bar 121. Consequently a back and forth movement will be imparted to the differential feed dog 114 during each rotation of the main shaft, and by adjusting the eccentric 142 the feed stroke of the dog may be varied.

The main feed dog 113 is attached to a forwardly and slightly downwardly inclined main feed bar 147. The front end of the bar is provided with a fork 148 which has sliding engagement with the pin 146 fixed to the differential feed bar 121 and consequently the front end of the main feed bar is supported by and moves upwardly and downwardly with said differential feed bar. The rear end of the main feed bar 147

is pivotally connected as at 149 to a rock arm 150 fixed to a sleeve or tubular feed travel shaft 151 which surrounds the differential feed travel shaft 138. A rock arm 152 is fixed to the tubular shaft 151 and this arm is oscillated from the driven counter shaft 132 by a pitman 153 which is pivotally connected as at 154 with said rock arm and has operative connection with the driven shaft through the medium of an adjustable eccentric 10 fixed to said driven shaft and indicated as an entirety by the numeral 155. Consequently a back and forth movement will be imparted to the main feed dog during each rotation of the main shaft, and by adjusting the eccentric 155 the feed 15 stroke of the dog may be varied.

From the foregoing, it will be seen that both feed dogs are moved upwardly and downwardly in unison, and that the feed travels of the dogs are independently adjustable.

20 In the operation of the feeding mechanism, let it be assumed that the differential feed bar 121 is beginning its upward stroke. The lever 124 is rocked about its fulcrum 125 and the feed bar is lifted until it engages the under face of the presser foot. The lever 124 then shifts its fulcrum to the pin 122 and consequently the original fulcrum 125 is moved downwardly taking the work clamp 97 therewith. This frees the fabric from its clamped condition between the foot and the 30 work clamp, and permits the feed dogs to function. At the end of the feed stroke, the original fulcrum is moved upwardly while the auxiliary feed bar is moved downwardly, whereby the work clamp will be restored to its initial clamping 35 position.

The ridge forming element and the driving mechanism therefor

Projecting upwardly through the front intermediate opening 101 of the work clamp and into the opening 22 of the presser foot is a ridge forming element H for presenting a ridge of fabric to the needle. When hemming operations are being performed the ridge will include the body fabric 40 A and the inner edge portion of the hem B. In some operations it is desirable to form some "anchor" stitches and some "skip" stitches, and sometimes it may be desirable to have the "anchor" stitches pass entirely through the body fabric. Various combinations of "anchor" and 45 "skip" stitches may be employed, such as, spaced "anchor" stitches with one or more intervening "skip" stitches. In the present instance, the ridge forming element H is constructed to effect 50 the formation of an "anchor" stitch followed by three "skip" stitches, or, it can be adjusted to form all "anchor" stitches. By removably mounting this element, another element may be substituted for forming alternate "anchor" and 55 "skip" stitches.

Located within the lower frame arm 14 is a rotary shaft 156 whose longitudinal axis lies in the vertical plane containing the needle path of movement. This shaft is journaled in spaced 60 right and left bearings 157, 158 of a lever arm 158 which is provided at its inner end with a transverse horizontal bearing 159 journaled on a stud 160 fixed to the front wall 161 of the frame arm 14. The outer or left end portion of the 65 shaft projects through the slot 105 of the end wall 104 of the lower frame arm 14 and through the vertical slot 98a of the shank 98 of the work support 97, and is provided at its outer end with an inwardly extending counter bore 162 and a 70 threaded bore 163. The ridge forming element 75

H, as shown in Figs. 29 and 30, is in the nature of a star disc, and this disc is provided with an integral hub 164 which is received by the counter bore 162 and the hub is provided with an integral threaded pin or reduced extension 164a which is threadedly engaged in the bore 163 whereby the disc may be readily removed. The disc, as shown in Figs. 2 and 29, is formed with spaced peripheral recesses forming resultant radial arms 165, 166, 167, 168, which are spaced 10 apart 90° and are arranged in tandem and in the same vertical plane. The radii of the arms 165, 166 and 167 are alike and consequently the outer ends or peripheral surfaces or portions 165a, 166a and 167a are concentric with respect 15 to the axis of the element. The trailing edges 165b, 166b, 167b and 168b of the arms are located in spaced parallel relation to the diametric axes of the arms, and the leading edges 165c, 166c, 167c and 168c are disposed at acute angles to 20 the diametric axes of the arms, with the apices of the angles facing in the direction of the axis of the disc. A supplemental arm 168d is slidably mounted in a radial slot 169 formed in one face of the arm 168, and is retained in any position 25 of radial adjustment by a screw and slot connection 170, the supplemental arm 168d being provided with a concentric peripheral surface or portion 168a. The leading edges of all the arms terminate at their outer ends in rearwardly 30 curved surfaces 165e, 166e, 167e, 168e which merge with the respective peripheries of the arms. The trailing edge of each arm meets the leading edge of the next adjacent arm at a point located inwardly from the chord of the arc which intersects the diametric axes of the arms at the peripheries thereof, as shown by the dotted lines in Fig. 29. The disc shaft 156 is pressed upwardly by a spring 171 located intermediate the supporting lever arm 158 and the bottom wall 109 of 40 the lower frame arm 14, and a manually operable screw 172 which is threaded downwardly into the top wall 173 of the lower frame arm 14 engages said lever arm and thereby enables the operator to vary the effective height of the disc 45 relative to the needle path, the spring also functioning to permit the disc to be automatically lowered when seams or thicker fabrics are fed through the machine. The disc shaft 156 is continuously rotated from the counter shaft 132 by a 50 driving connection which in the present instance includes a reduction gear coupling having a 4-to-1 ratio. Although, I have specifically shown and described a gear coupling between these shafts, any other known mechanical reduction 55 driving means may be employed and I therefore use the term "reduction gear coupling" in its broadest sense. To this end, a relatively small gear 174 which is fixed to the counter shaft 132 within the frame standard 5, drives a relatively 60 large gear 175 which is loose on a stub shaft 176 fixed to the standard, the ratio being 2-to-1. Fixed to the gear 175 is a gear 177 of the same diameter as the gear 174, and this gear 177 drives a gear 178 which is loose on the counter shaft 65 132, the ratio of the gears 177, 178 being 1-to-2. Fixed to the gear 178 is a gear 179 and fixed to the disc shaft 156 adjacent the transverse pivot 160 thereof is a gear 180 which is in constant mesh with the driven gear 179, the ratio of the 70 gears 179, 180 being 1-to-1, and consequently the disc will be rotated once during every four revolutions of the main shaft. The teeth of the gears 179, 180 are so constructed as to permit the upward and downward swinging of the disc 75

shaft 156 without any binding. The disc is rotated rearwardly in timed relation to the needle reciprocations whereby the peripheral portions of the disc arms will be successively positioned 5 under the needle path substantially when the needle is beginning its forward stroke. Thus when the three arms 165, 166 and 167 are each positioned under the needle path, the needle will enter and emerge from the hem only and there- 10 by form a "skip" stitch, and when the arm 168^d is under the needle path the needle will enter and emerge from the body fabric and then enter and emerge from the hem and thereby form an "anchor" stitch.

15 *Means for depressing the work clamp, the feed and the ridge forming element*

The upper end of the chain 111 previously described is connected to the free end of the lever 20 arm 158 which supports the disc shaft 156. An interponent or bar 181 is mounted in a horizontal groove 182 formed in the shank 98 of the work clamp 97 for sliding movements across the vertical opening 98^a of said shank, the interponent 25 being formed along its upper edge with a recess 183. The interponent is retained in its groove or seat 182 by a flat spring 184 attached to the shank 98, and the forward movement of the interponent is limited by a stop 185 carried thereby and engaging the rear edge of the shank. An opening 186 is formed in the forward end of the interponent for facilitating the forward movement thereof. The disc shaft 156 projects 30 through the slot 98^a above the interponent. 35 When the interponent is in its forward position the recess 183 will not register with the slot 98^a and consequently the disc shaft when depressed by the chain 111 will engage said interponent and thereby depress the work clamp together 40 with the feed so as to permit the ready insertion of fabric in the machine, or removal therefrom. When, however, it is desirable to remove the ridge forming element H from the shaft 156 45 for the purpose of substituting another element, it is necessary to provide means for lowering the element below the presser foot and the work clamp in order for the element to clear the latter, and for this purpose the interponent 181 is moved rearwardly until the recess 183 there- 50 in registers with the opening 98^a of the shank 98 of the work clamp. The operator can then depress the shaft 156 into the recess 183 and thereby position the disc H entirely below the work support whereby the disc may be readily 55 removed from the shaft and another disc substituted thereon.

It will, therefore, be seen that the shaft 156 is substantially horizontal at all times; that by having the fulcrum 159 located within the frame 60 standard 5 the ridge forming element H will have a long radius and consequently the element will move in a substantially vertical plane when it is depressed by reason of cross seams passing thereover and the ridge of fabric will not be 65 come distorted by said movement; that the upper portion of said element normally projects upwardly through the opening 101 of the work clamp 97 and into the presser foot opening 22, and consequently when it is desired to remove 70 the element from the shaft it is necessary to swing the shaft downwardly until the element clears the work clamp; that when the interponent 181 is in its rearmost position, the shaft may be swung downwardly by a pull on the chain 75 111 without depressing the work clamp and the

feed, and that when the interponent is in its foremost position the work clamp, the feed, and the element will be depressed by a pull on the chain to thereby permit the ready insertion of work into the machine or the removal of work 5 therefrom.

The rotation of the disc H is timed with the needle reciprocations whereby a given arm of the disc will ridge the fabric immediately in advance of the needle penetrating the ridge, and 10 the periphery of the arm is of sufficient length to support the ridge until the needle point enters the needle guide on the right hand side of the foot, whereby the ridge of fabric will be supported by the needle until the latter on its return 15 stroke leaves the fabric. By providing deep spaces between the arms as shown and described, the fabric will not be ridged during the feed action which occurs immediately after the needle is withdrawn from the fabric, and consequently 20 the differential feed dog 114 will function at its maximum efficiency.

I may desire to substitute a non-threaded looper or spreader for the threaded looper 31 in which case both loop takers will cooperate with 25 each other and with the needle to form an over-edge flat seam employing only a single thread, as shown in Figure 24, or I may desire to substitute a threaded looper for the spreader 32 in which case both loopers will cooperate with each 30 other and with the needle to form a flat over-edge seam employing three threads, as shown in Figure 25.

In Figure 32, I have illustrated a flat seam 35 which may be produced by my machine after first removing the trimming mechanism. In this figure, a fabric section X is superposed on a base section Y, and the edge of the former is joined to the latter by a line of blind stitches, 40 preferably formed by the two threads C, D, as shown in Fig. 19.

As shown in Figures 26 and 27, a ridge forming disc I may be employed. The peripheral surfaces 187 of the radial arms 188 are formed with circumferentially extending grooves 189 45 forming resultant spaced ridge forming shoulders 190, 191. The grooves are disposed in alignment and in the vertical plane containing the needle shaft 25. Consequently, the needle will enter and emerge from the base fabric at two spaced 50 points prior to the needle moving upwardly through the hem fold. This results in each needle loop passing into and out of the body fabric at two spaced points 192, 192, as shown in Fig. 28, when "anchor" stitches are being formed. 55

It will be seen that the edge portion of the hem fold immediately after leaving the hemmer, is directed upwardly by the opening 71 and is then trimmed by the cooperating horizontal cutting elements 79, 82. The trimmed edge portion of the hem fold is then turned down against the body fabric by engaging the bridge on the presser foot between the aligned openings 71 and 22 whereby the entire trimmed hem fold will be positioned flat against the body fabric immediately 60 prior to the same being engaged by the ridge forming element H. Immediately thereafter the hem fold will be joined to the body fabric by the line of blind stitches in which the needle thread loops first enter the body fabric and pass upwardly through the hem fold and are concatenated by a covering thread which is formed into loops overlying the trimmed edge of the hem fold. This produces an extremely flat and covered hem fold. It will be observed by reference 70 75 76 to

to Figure 6 of the drawings that the shaft 156 has a free end portion extending beyond the left hand bearing 157. By removably mounting the ridge forming element on the free end of this 5 shaft in the manner illustrated in Figures 30 and 31 of the drawings, the ridge forming element may be removed with facility without disturbing the mounting of the shaft.

It is of course to be understood that the details 10 of structure and arrangement of parts may be variously changed and modified without departing from the spirit and scope of my invention.

I claim:

1. In a sewing machine stitch forming mechanism, the combination with a horizontal presser foot having an opening, of means for projecting a ridge of body fabric upwardly through the opening into needle penetrating position, and a stitch forming mechanism operating entirely 20 above the foot and including a threaded needle mounted for horizontal reciprocations across the ridge forming means, and two oscillatory loop takers cooperating with each other and with the needle, said loop takers being each fulcrumed on 25 an axis located in rear of the needle path, one of said loop takers being fulcrumed on a horizontal axis.

2. In a sewing machine stitch forming mechanism, the combination with a horizontal presser 30 foot having an opening, of means for projecting a ridge of body fabric upwardly through the opening into needle penetrating position, and a stitch forming mechanism operating entirely above the foot and including a threaded needle 35 mounted for horizontal reciprocations across the ridge forming means, and two oscillatory loop takers cooperating with each other and with the needle, one of said loop takers being fulcrumed on a vertically inclined axis located in rear of 40 the needle path and the other loop taker being fulcrumed on a horizontal axis inclined to the needle path and located in rear of the needle path, the first mentioned loop taker moving in a 45 path inclined to the needle path and the second mentioned loop taker intersecting the needle path.

3. In a sewing machine, the combination with 50 a frame having a main shaft journaled therein, of a horizontal presser foot fixed to said frame and provided with an opening, ridge forming means for projecting a ridge of fabric upwardly through the opening into needle penetrating position, an oscillatory needle shaft journaled on the frame above the foot and operatively connected with the main shaft, a needle carried by 55 said needle shaft for reciprocations across said ridge forming means, a loop taker fulcrumed on the foot in rear of the needle path for reciprocations in a path in front of and in a path diagonal to the needle path, a loop taker fulcrumed on a horizontal axis located on the frame in rear of the needle path for reciprocations intersecting said path, and separate driving connections between the loop takers and the main shaft.

4. In a sewing machine, the combination with 60 a frame having a main shaft journaled therein, of a horizontal presser foot fixed to said frame and provided with an opening, ridge forming means for projecting a ridge of fabric upwardly 65 through the opening into needle penetrating position, an oscillatory needle shaft journaled on the frame above the foot and operatively connected with the main shaft, a needle carried by 70 said needle shaft for reciprocations across said ridge forming means, a loop taker fulcrumed on

the foot in rear of the needle path for reciprocations in a path in front of and in a path diagonal to the needle path and movable downwardly across the ridge forming means to a point below the needle path, a loop taker fulcrumed on a horizontal axis on the frame in rear of the needle path for reciprocations intersecting said needle path and movable upwardly from a point in rear of the needle path to a point in front of the path of movement of the first mentioned loop taker, 10 the fulcra of said loop takers being located on the side of the ridge forming means opposite the needle when the latter is at the beginning of its forward stroke, and separate driving connections between the loop takers and the main shaft. 15

5. In a sewing machine, the combination with a frame having a main shaft journaled therein, of a horizontal presser foot fixed to said frame and provided with an opening, ridge forming means for projecting a ridge of fabric upwardly 20 through the opening into needle penetrating position, an oscillatory needle shaft journaled on the frame above the foot and operatively connected with the main shaft, a needle carried by said needle shaft for reciprocations across said ridge 25 forming means, a bell crank lever fulcrumed on the presser foot in rear of the needle path and including a forwardly extending arm, a loop taker mounted on the forwardly extending arm for reciprocations in front of and in a path diagonal 30 to the needle path, driving connections between the other arm of said bell crank lever and the main shaft including a bell crank lever fulcrumed on a horizontal axis, a loop taker fulcrumed in rear of the needle path for cooperation 35 with the needle and with the first mentioned loop taker, and means for operating said second mentioned loop taker.

6. In a sewing machine, the combination with a frame having a main shaft journaled therein, of a horizontal presser foot fixed to said frame and provided with an opening, ridge forming means for projecting a ridge of fabric upwardly through the opening into needle penetrating position, an oscillatory needle shaft journaled on the frame above the foot and operatively connected with the main shaft, a needle carried by 40 said needle shaft for reciprocations across said ridge forming means, a bell crank lever fulcrumed on the presser foot in rear of the needle path and including a forwardly extending arm, a loop taker mounted on the forwardly extending arm for reciprocations in front of and in a path diagonal 45 to the needle path, driving connections between the other arm of said bell crank lever and the main shaft including a bell crank lever fulcrumed on a horizontal axis, a loop taker fulcrumed on the frame in rear of the needle path for cooperation 50 with the needle and with the first mentioned loop taker, and driving connections between the main shaft and the second mentioned loop taker. 55

7. In a sewing machine, the combination with a frame including a standard and an arm extending laterally from the upper end thereof and terminating in an arm extension and an end wall, of a main shaft journaled in said arm and having an end portion extending above the arm extension and journaled in said end wall, a horizontal presser foot disposed below and fixed to 60 said arm extension and provided with an opening, means for projecting a ridge of material upwardly through the opening into needle penetrating position, a threaded needle supported by 65 said arm for horizontal reciprocations across said arm for horizontal reciprocations across said 70 75

ridge forming means, two loop takers cooperating with each other and with the needle, and separate driving means for said loop takers including an eccentric fixed to the main shaft above

5 the arm extension and operating connections between one of said loop takers and said eccentric.

8. In a sewing machine, the combination with a frame including a standard and an arm extending laterally from the upper end thereof and terminating in an arm extension and an end wall, of a main shaft journaled in said arm and having an end portion extending above the arm extension and journaled in said end wall, a horizontal presser foot disposed below and fixed to 10 said arm extension and provided with an opening, means for projecting a ridge of material upwardly through the opening into needle penetrating position, a threaded needle supported by said arm for horizontal reciprocations across said 15 ridge forming means, two loop takers cooperating with each other and with the needle, a lever fulcrumed on the foot and supporting one of said loop takers, a lever fulcrumed on the arm for supporting the other loop taker, and separate 20 driving connections between said levers and the main shaft including separate eccentrics fixed to the main shaft above the arm extension.

9. In a sewing machine, the combination with a frame including a standard and an arm extending laterally from the upper end thereof and terminating in an arm extension and an end wall, of a main shaft journaled in said arm and having an end portion extending above the arm extension and journaled in said end wall, a horizontal presser foot disposed below and fixed to 30 said arm extension and provided with an opening, means for projecting a ridge of material upwardly through the opening into needle penetrating position, a threaded needle supported by 35 said arm for horizontal reciprocations across said ridge forming means, a bell crank lever fulcrumed on the foot in rear of the needle path to swing about a vertically inclined axis and including a forwardly extending arm, a loop taker 40 mounted on the forwardly extending arm for reciprocations in front of and in a path inclined to the needle path, driving connections between the other arm of the bell crank lever and the main shaft including an eccentric fixed to said 45 shaft above the arm extension, a lever fulcrumed intermediate its ends on the arm extension in front of the needle path to swing about a horizontal axis inclined to the needle path, a loop taker mounted on the lower arm of said lever for 50 reciprocations in a path intersecting the needle path, and driving connections between the upper arm of said lever and the main shaft including an eccentric fixed to said shaft above the arm extension.

60 10. In a sewing machine, the combination with a frame including a standard and an arm extending laterally from the upper end thereof and terminating in an arm extension and an end wall, of a main shaft journaled in said arm and having an end portion extending above the arm extension and journaled in said end wall, a horizontal presser foot disposed below and fixed to 65 said arm extension and provided with an opening, a horizontal needle shaft extending at an angle to the main shaft and journaled in said shaft extension above the opening, a needle carried by said needle shaft for oscillations across the presser foot opening, a loop taker supported by the arm extension for cooperation with the needle, separate eccentrics fixed to the main shaft

above the arm extension, and separate driving connections between the needle shaft and one eccentric and between the loop taker and the other eccentric.

11. In a sewing machine, the combination with a frame including a standard and an arm extending laterally from the upper end thereof, of a main shaft journaled in said arm, a horizontal presser foot fixed to the free end of the arm below the main shaft and provided with an opening, means for projecting a ridge of body fabric upwardly through the opening into needle penetrating position, a horizontal needle shaft journaled in the free end of the said arm above said opening, a curved needle carried by said needle shaft, driving connections between the main shaft and the needle shaft for reciprocating the needle across the ridge forming means from left to right in its penetrating stroke, a vertical lever fulcrumed intermediate its ends on the frame arm to swing about a horizontal axis, a spreader fixed to the lower arm of said lever, driving connections between the upper arm of the lever and the main shaft, a bell crank lever fulcrumed on said foot, a threaded looper fixed 25 to said bell crank lever, and driving connections between the looper lever and the main shaft, the spreader engaging and spreading the needle thread loop into position for entrance by the looper, and the looper entering the needle thread loop and then moving the looper thread loop into 30 position to be entered by the needle.

12. In a sewing machine, the combination with a frame, having a main shaft journaled therein of a horizontal presser foot fixed to said frame and provided with an opening, ridge forming means for projecting a ridge of fabric upwardly through the opening into needle penetrating position, an oscillatory needle shaft journaled on the frame above the foot and operatively connected with the main shaft, a needle carried by said needle shaft for reciprocations across said ridge forming means, a threaded looper fulcrumed on the foot in rear of the needle path for reciprocations in a path in front of and in a path 40 diagonal to the needle path and operatively connected with the main shaft, a spreader fulcrumed on a horizontal axis located on the frame in rear of the needle path for reciprocations intersecting said path and operatively connected with the 45 main shaft, the spreader engaging and spreading the needle thread loop into position to be entered by the looper, and the looper entering the spread needle thread loop and then moving the 50 looper thread loop into position to be entered by the needle.

13. In a sewing machine stitch forming mechanism, the combination with a horizontal presser foot having an opening, of means for projecting a ridge of body fabric upwardly through the opening into needle penetrating position, a chain-off finger pivotally mounted on the foot and projecting rearwardly along the opening above the ridge forming means, means for yieldably retaining said finger against upward movement, 65 and a stitch forming mechanism operating entirely above the foot and including a threaded needle mounted for horizontal reciprocations across the ridge forming means and under the finger, and two reciprocatory loop takers cooperating with each other and with the needle for moving a thread loop over the finger into position to be entered by the needle.

14. In a sewing machine stitch forming mechanism, the combination with a horizontal presser 70

foot having an opening, of means for projecting a ridge body fabric upwardly through the opening into needle penetrating position, a stitch forming mechanism operating entirely above the foot 5 and including a threaded needle mounted for horizontal reciprocations across the ridge forming means, two reciprocatory loop takers cooperating with each other and with the needle, a chaining-off finger projecting rearwardly along 10 the opening above the ridge forming means, a lever fulcrumed intermediate its ends on the foot for supporting said finger at its front end, and yieldable means interposed between the rear end 15 of the lever and the foot for yieldably retaining the finger against upward movement.

15. In a sewing machine stitch forming mechanism, the combination with a horizontal presser foot having an opening, of means for projecting a ridge of body fabric upwardly through the opening 20 into needle penetrating position, a stitch forming mechanism operating entirely above the foot and including a threaded needle mounted for horizontal reciprocations across the ridge forming means, two reciprocatory loop takers 25 cooperating with each other and with the needle, a chaining-off finger projecting rearwardly along the opening above the ridge forming means, a lever fulcrumed on the foot for supporting said finger, and yieldable means interposed between 30 the lever and the foot for yieldably retaining the finger against upward movement.

16. In a sewing machine stitch forming mechanism, the combination with a horizontal presser foot having an opening, of means for projecting a ridge of body fabric upwardly through the opening 35 into needle penetrating position, a stitch forming mechanism operating entirely above the foot and including a threaded needle mounted for horizontal reciprocations across the ridge forming means, two reciprocatory loop takers 40 cooperating with each other and with the needle, and a vertically yieldable chaining-off finger projecting rearwardly above the ridge forming means, said needle having its path of movement under 45 the finger and one of said loop takers having its movement across and over said finger.

17. In a sewing machine, a horizontal presser foot having an opening, a stitch forming mechanism including a needle mounted for horizontal reciprocations above the opening, a rotatable element 50 mounted below the foot for projecting a ridge of fabric upwardly through the opening into needle penetrating position, and means for imparting continuous rotary motion to said element.

55. 18. In a sewing machine, the combination with a presser foot having an opening, of a main shaft, a stitch forming mechanism including a needle mounted for horizontal reciprocations above the opening and having driving connections with said shaft, a rotatable element mounted below the foot and provided with a plurality of peripheral portions arranged in tandem for successively projecting ridges of fabric upwardly through the opening into needle penetrating position, and driving connections between the main shaft and the element for continuously rotating said element in timed relation to the needle reciprocations.

60. 19. In a sewing machine, the combination with 70 a presser foot having an opening, of a main shaft, a stitch forming mechanism including a needle mounted for horizontal reciprocations above the opening and having driving connections with said shaft, a rotatable element mounted below

the foot and provided with a plurality of peripheral portions arranged in tandem for successively projecting ridges of fabric upwardly through the opening into needle penetrating position, and driving connections including a reduction gear coupling between the main shaft and the element for continuously rotating said element in timed relation to the needle reciprocations, the number of rotations of the main shaft to one rotation of the element corresponding to 10 the number of peripheral portions of the element.

20. In a blind stitch sewing machine, a horizontal presser foot having an opening, a stitch forming mechanism including a needle mounted for horizontal reciprocations above the opening, 15 a rotatable element mounted below the foot and provided with a plurality of spaced radial arms having concentric peripheral portions for projecting a ridge of fabric upwardly through the opening into needle penetrating position, each 20 arm having a trailing edge disposed in parallelism to the diametric axis of the arm, and a leading edge disposed at an acute angle to said diametric axis with the apex of the angle facing towards the center of the element, the trailing edge of 25 one arm meeting the leading edge of the next adjacent arm at a point located inwardly from the chord of the arc intersecting the diametric axis of said adjacent arms at the peripheries thereof, and means for imparting rotary motion 30 to said element.

21. In a sewing machine, the combination with a presser foot having an opening, of a main shaft, a stitch forming mechanism including a needle mounted for horizontal reciprocations 35 above the opening and having driving connections with said shaft, a rotatable element mounted below the foot and provided with a plurality of spaced radial arms having concentric peripheral portions arranged in tandem for successively projecting ridges of fabric upwardly through the opening into needle penetrating position, each arm having a trailing edge disposed in parallelism to the diametric axis of the arm, and a leading edge disposed at an acute angle to said 40 diametric axis with the apex of the angle facing towards the center of the element, the trailing edge of one arm meeting the leading edge of the next adjacent arm at a point located inwardly from the chord of the arm intersecting the diametric axis of said adjacent arms at the peripheries thereof, and driving connections between the main shaft and the element for rotating said 45 element in timed relation to the needle reciprocations.

22. In a sewing machine, the combination with a presser foot having an opening, of a main shaft, a stitch forming mechanism including a needle mounted for horizontal reciprocations above the opening and having driving connections with said shaft, a rotatable element mounted below the foot and provided with a plurality of spaced radial arms having concentric peripheral portions arranged in tandem for successively projecting ridges of fabric upwardly through the opening into needle penetrating position, each arm having a trailing edge disposed in parallelism to the diametric axis of the arm, and a leading edge disposed at an acute angle to said 55 diametric axis with the apex of the angle facing towards the center of the element, the trailing edge of one arm meeting the leading edge of the next adjacent arm at a point located inwardly from the chord of the arm intersecting the diametric axis of said adjacent arms at the peripheries thereof, and driving connections between the main shaft and the element for rotating said 60 element in timed relation to the needle reciprocations.

eries thereof, and driving connections including a reduction gear coupling between the main shaft and the element for continuously rotating said element in timed relation to the needle reciprocations, the number of rotations of the main shaft to one rotation of the element corresponding to the number of peripheral portions of the element.

23. In a sewing machine, the combination with a presser foot having an opening, of a main shaft, a stitch forming mechanism including a needle mounted for horizontal reciprocations above the opening and having driving connections with said shaft, a counter shaft, a one-to-

15 one driving connection between the main shaft and the counter shaft, a rotatable element mounted below the foot and provided with a plurality of peripheral portions arranged in tandem for successively projecting ridges of fabric upwardly through the opening into needle penetrating position, and driving connections including a reduction gear coupling between the counter shaft and the element for continuously rotating said element in timed relation to the needle reciprocations, the number of rotations of the main shaft to one rotation of the element corresponding to the number of peripheral portions of the element.

24. In a sewing machine, the combination with a hollow standard having a laterally extending arm, of a main shaft journaled in said standard and arm, a horizontal presser foot fixed to said arm and having an opening, a stitch forming mechanism supported on said arm and operating entirely above the foot and including a needle having reciprocations across said opening, a rotatable element mounted below the foot for projecting a ridge of fabric upwardly through the opening into needle penetrating position, a horizontal shaft on which the ridge forming element is mounted, and driving connections between the main shaft and the element supporting shaft for imparting continuous rotary motion to said element.

25. In a sewing machine, the combination with a hollow standard having a laterally extending arm, of a main shaft journaled in said standard and arm, a horizontal presser foot fixed to said arm and having an opening, a stitch forming mechanism supported on said arm and operating entirely above the foot and including a needle having reciprocations across said opening, a rotatable element mounted below the foot for projecting a ridge of fabric upwardly through the opening into needle penetrating position, a horizontal shaft on which the ridge forming element is mounted, and driving connections between the main shaft and the element supporting shaft for imparting continuous rotary motion to said element comprising a counter shaft mounted in the standard, a one-to-one gear coupling between the main shaft and the counter shaft, and a reduction gear coupling between the counter shaft and the element supporting shaft.

26. In a sewing machine, the combination with a hollow standard having a laterally extending arm, of a main shaft journaled in said standard and arm, a horizontal presser foot fixed to said arm and having an opening, a stitch forming mechanism supported on said arm and operating entirely above the foot and including a needle having reciprocations across said opening, a rotatable element mounted below the foot and provided with a plurality of peripheral portions arranged in tandem for successively projecting

ridges of fabric upwardly through the opening into needle penetrating position, a horizontal shaft on which the element is mounted, and driving connections between the main shaft and the element supporting shaft for imparting continuous rotary motion to said element comprising a counter shaft mounted in the standard, a one-to-one gear coupling between the main shaft and the counter shaft, and a reduction gear coupling between the counter shaft and the element supporting shaft, the number of rotations of the main shaft to one rotation of the element corresponding to the number of peripheral portions of the element.

27. In a sewing machine, a horizontal presser foot having an opening, a stitch forming mechanism including a needle mounted for horizontal reciprocations above the opening, a rotatable element mounted below the foot for projecting a ridge of fabric upwardly through the opening into needle penetrating position, said element including a radially adjustable peripheral surface whereby the effective height thereof relative to the needle path may be varied, and means for imparting rotary motion to said element.

28. In a sewing machine, the combination with a presser foot having an opening, of a main shaft, a stitch forming mechanism including a needle mounted for horizontal reciprocations above the opening and having driving connections with said shaft, a rotatable element mounted below the foot and provided with a plurality of peripheral portions arranged in tandem for successively projecting ridges of fabric upwardly through the opening into needle penetrating position, one of said peripheral surfaces being radially adjustable to vary its effective position with respect to the needle path, and driving connections between the main shaft and the element for rotating said element in timed relation to the needle reciprocations.

29. In a sewing machine, the combination with a presser foot having an opening, of a main shaft, a stitch forming mechanism including a needle mounted for horizontal reciprocations above the opening and having driving connections with said shaft, a rotatable element mounted below the foot and provided with a plurality of peripheral portions arranged in tandem for successively projecting ridges of fabric upwardly through the opening into needle penetrating position, one of said peripheral surfaces being radially adjustable to vary its effective position with respect to the needle path, and driving connections including a reduction gear coupling between the main shaft and the element for continuously rotating said element in timed relation to the needle reciprocations, the number of rotations of the main shaft to one rotation of the element corresponding to the number of peripheral portions of the element.

30. A rotatable ridge forming element for sewing machines comprising a plurality of radially extending arms arranged in tandem and having their outer ends forming concentric peripheral portions, each arm having a trailing edge disposed in parallelism to the diametric axis of the arm, and a leading edge disposed at an acute angle to said diametric axis with the apex of the angle facing towards the center of the element, the trailing edge of one arm meeting the leading edge of the next adjacent arm at a point located inwardly from the chord of the arc intersecting the diametric axis of said adjacent arms at the peripheries thereof.

31. A rotatable ridge forming element for sew-

ing machines comprising a plurality of radially extending arms arranged in tandem and having their outer ends forming concentric peripheral portions, each arm having a trailing edge disposed in parallelism to the diametric axis of the arm, and a leading edge disposed at an acute angle to said diametric axis with the apex of the angle facing towards the center of the element, the outer end of the leading edge being curved rearwardly and merging with the peripheral surface of the arm, the trailing edge of one arm meeting the leading edge of the next adjacent arm at a point located inwardly from the chord of the arc intersecting the diametric axis of said adjacent arms at the peripheries thereof.

32. A rotatable ridge forming element for sewing machines comprising a plurality of relatively fixed and radially adjustable arms arranged in tandem.

33. A rotatable ridge forming element for sewing machines comprising a plurality of relatively fixed and radially adjustable arms arranged in tandem and having concentric portions at their outer ends.

34. A rotatable ridge forming element for sewing machines comprising a plurality of relatively fixed and radially adjustable arms arranged in tandem, each arm having a trailing edge disposed in parallelism to the diametric axis of the arm, and a leading edge disposed at an acute angle to said diametric axis with the apex of the angle facing towards the center of the element, the trailing edge of one arm meeting the leading edge of the next adjacent arm at a point located inwardly from the chord of the arc intersecting the diametric axis of said adjacent arms at the peripheries thereof.

35. A rotatable ridge forming element for sewing machines comprising a plurality of relatively fixed and radially adjustable arms arranged in tandem, each arm having a trailing edge disposed in parallelism to the diametric axis of the arm, and a leading edge disposed at an acute angle to said diametric axis with the apex of the angle facing towards the center of the element, the outer end of the leading edge being curved rearwardly and merging with the peripheral surface of the arm, the trailing edge of one arm meeting the leading edge of the next adjacent arm at a point located inwardly from the chord of the arc intersecting the diametric axis of said adjacent arms at the peripheries thereof.

36. In a sewing machine, the combination with a horizontal presser foot having an opening, of a curved needle supported on an axis located above the foot to oscillate across said opening, and a ridge forming disc for projecting a ridge of fabric upwardly through the foot into needle penetrating position, said disc having an interrupted peripheral surface provided with an interrupted circumferentially extending groove forming resultant spaced ridge forming ribs, the groove being directly below the axis of the needle.

37. In a sewing machine, the combination with a horizontal presser foot having an opening, of a curved needle supported on an axis located above the foot to oscillate across said opening, a ridge forming disc for projecting a ridge of fabric upwardly through the foot into needle penetrating position, said disc having a plurality of spaced peripheral surfaces arranged in tandem, each surface being provided with a circumferentially extending groove forming resultant spaced ridge forming ribs, the groove being directly below the axis of the needle, and means for continuously

rotating said disc comprising a main shaft, and driving connections including a reduction gear coupling between the shaft and the disc, the number of rotations of the shaft to one rotation of the disc corresponding to the number of peripheral surfaces of the disc.

38. A ridge forming disc for sewing machines having an interrupted peripheral portion provided with an interrupted circumferentially extending groove forming resultant spaced ridge forming surfaces.

39. A ridge forming disc for sewing machines having a plurality of spaced peripheral portions arranged in tandem, each portion being provided with a circumferentially extending groove forming resultant spaced ridge forming surfaces.

40. A rotatable ridge forming element for sewing machines comprising a plurality of radially extending arms arranged in tandem, the outer end of each arm being provided with a circumferentially extending groove forming resultant spaced ridge forming ribs.

41. A rotatable ridge forming element for sewing machines comprising a plurality of radially extending arms arranged in tandem, the outer end of each arm having a concentric peripheral surface provided with a circumferentially extending groove forming resultant spaced ridge forming ribs.

42. In a sewing machine, a ridge forming element having a laterally extending hub provided with a reduced and threaded extension, and a shaft having a counterbore at one end for receiving said hub and with a threaded bore for receiving said extension.

43. In a sewing machine, the combination with a frame, of a horizontal presser foot fixedly secured to said frame and provided with an opening, of a vertically movable work clamp located below the foot, a stitch forming mechanism located above the foot and including a needle mounted for reciprocations across the opening, means for projecting a ridge of fabric upwardly through said opening into needle penetrating position, and means for feeding the fabric comprising a main feed dog and a differential feed dog operating respectively in rear of and in front of the needle path, and means for imparting differential feed movements to said dogs.

44. In a sewing machine, the combination with a frame, of a horizontal presser foot fixedly secured to said frame and provided with an opening, of a vertically movable work clamp located below the foot, a stitch forming mechanism located above the foot and including a needle mounted for reciprocations across the opening, means for projecting a ridge of fabric upwardly through said opening into needle penetrating position, and means for feeding the fabric comprising a main feed dog and a differential feed dog located below the foot and cooperating with the underface thereof, said feed dogs operating respectively in rear of and in front of the needle path, and means for imparting differential feed movements to said dogs.

45. In a sewing machine, the combination with a frame, of a horizontal presser foot fixedly secured to said frame and provided with an opening, of a vertically movable work clamp located below the foot, a stitch forming mechanism located above the foot and including a needle mounted for reciprocations across the opening, means for projecting a ridge of fabric upwardly through said opening into needle penetrating position, and means for feeding the fabric com-

prising a main feed dog and a differential feed dog located below the foot and cooperating with the underface thereof, said feed dogs operating respectively in rear of and in front of the needle path and one of said dogs having feed sections disposed on opposite sides of the ridge forming means, and means for imparting differential feed movements to said dogs.

46. In a sewing machine, the combination with 10 a frame, of a horizontal presser foot fixedly secured to said frame and provided with an opening, of a vertically movable work clamp located below the foot, a stitch forming mechanism located above the foot and including a needle 15 mounted for reciprocations across the opening, means movable upwardly and downwardly with the work clamp for projecting a ridge of fabric upwardly through said opening into needle penetrating position, a differential feed movable up 20 and down with the work clamp and cooperating with the underface of the foot and including a feed dog having feed sections arranged on opposite sides of the ridge forming means, yieldable means for retaining the work clamp against depression, and means for depressing said clamp 25 together with the ridge forming means and said differential feed.

47. In a sewing machine, the combination with 30 a frame including a standard and an arm extending laterally from the upper end thereof and

terminating in an arm extension and an end wall, of a main shaft journaled in said arm and having an end portion extending above the arm extension and journaled in said end wall, a horizontal presser foot disposed below and fixed to 5 said arm extension and provided with an opening, stitch forming instrumentalities mounted on the arm and operating entirely above the foot, and driving connections for said instrumentalities having operative connections with the main shaft 10 above said arm extension.

48. In a sewing machine of the type described, the combination comprising a presser foot having an opening therethrough, stitch-forming mechanism including a needle disposed at one 15 side of the presser foot and means for actuating the needle across the presser foot opening, and node-forming mechanism disposed at the other side of the presser foot for projecting a node of material through the opening in the presser foot 20 and into the path of the needle including a shaft movable about its axis, a bearing for the shaft, said shaft including a free end portion extended beyond said bearing to a point beneath the presser foot, and a node former removably mounted 25 on the free end of said shaft whereby it can be readily removed without disturbing the mounting of said shaft.

HORACE F. GRUMAN.
